ATTORNEY

UNITED STATES PATENT OFFICE.

DAVID BACHER, OF NEW YORK, N. Y.

DISPLAY DEVICE.

1,356,588.

Specification of Letters Patent. Patented Oct. 26, 1920.

Application filed January 3, 1920. Serial No. 349,255.

To all whom it may concern:

Be it known that I, DAVID BACHER, a citizen of the United States, residing at New York city, in the county and State of New York, have invented certain new and useful Improvements in Display Devices, of which the following is a specification.

My invention relates to an improved display device, designed more particularly to 10 display such articles as bow neckties.

Such display devices as at present generally used comprise a receptacle having attached therein a stepped display board provided with oppositely arranged incisions 15 into which the ends of the stiff tabs of the ties are inserted, thus holding the ties in display position. These display devices are rather expensive to manufacture and considerable skill is required and time consumed in attaching the ties to and removing 20 them from the display board.

The principal object of my invention is to provide an improved display device of simple and inexpensive construction, in 25 which the display board may be cut by a single die, and which will easily accommodate and satisfactorily retain ties of varying sizes.

The preferred embodiment of the invention 30 is illustratively exemplified in the accompanying drawing in which Figure 1 is a perspective view of the complete device with the cover removed; Fig. 2 is a development of a fragment of the display board; Fig. 3 is a perspective view of a part of the display board showing one compartment thereof; Fig. 4 is a cross sectional view on the line 4—4 of Fig. 3; and Fig. 5 is a similar view 35 on the line 5—5 of Fig. 3.

As shown in the drawing the device 40 comprises two principal parts, *i. e.*, the receptacle A and the display board B. The former is a relatively shallow box, preferably rectangular, of any desired dimensions, while 45 the latter embodies the features of my invention.

In forming the display board, preferably 50 by means of a single cutting and scoring die, I employ a flat blank of flexible material such as cardboard. The blank is scored along the lines 10 and 11 to permit the end and side flaps 12 and 13, respectively, to be turned down as shown in Fig. 3 and support the board within the box A. The blank is

also scored along the lines 14 and 15 to form 55 the hinge joints for the side tie-retaining flaps 16 and 17 and along the lines 18 and 19 to form the hinge joints for the end tie-retaining flaps 20 and 21. Between the score lines 14 and 15 the blank is cut along 60 the line 22, this cut extending to the cuts 23 and 24, extending at right angles to the cut 22, and defining the outer ends or margins of the flaps 20 and 21. Cuts 25 are formed at either end of the score line 14, and 65 similar cuts 26 at either end of the score line 15, these cuts 25 and 26 defining the sides of the side tie-retaining flaps 20 and 21.

Between the score lines 10 and 14 at either 70 end of the blank an intact part 27 of the blank is left to form the opposite ends of the display board. Similar intact parts 28 are left between the score lines 11 and 19 to form the sides of the board and transverse intact parts 29 are left to form the divisions 75 between the compartments in which the ties 30 are placed.

The display boards may be shipped flat, and may be set up for use by turning down 80 the end and side flaps 12 and 13 and placing the board in the receptacle A. The ties 30 may be placed in position by inserting them between the tie-retaining flaps 16—17 and 20—21 in each compartment. As the 85 ties are inserted the flaps are moved aside and owing to their flexibility lightly engage the opposite sides and ends of the ties. The flaps are sufficiently stiff and strong to hold the ties in position, yet owing to their flexibility and hinge connection with the blank 90 body they are adapted to accommodate and satisfactorily retain ties varying considerably in size.

With the construction described above no 95 particular skill is required either to remove the ties, or to properly replace them, inasmuch as the tie-retaining flaps will act automatically to position a tie centrally in a compartment after a tie has been inserted therein.

I claim:—

A display device, including a display board having longitudinally and transversely extending intact blank portions forming compartments, and parallel sided 105 article retaining flaps hinged to the edges of the several blank portions, there being four of said flaps arranged in oppositely dis-

posed pairs extending into each compartment, the end flaps in each compartment extending the full width of the latter while the side flaps terminate at intermediate points of the longer sides of the compartment and have a space at each lateral edge thereof.

In testimony whereof I have affixed my signature in presence of two witnesses.

DAVID BACHER.
